JOHN R. KUENEMANN, OF OAKLAND, CALIFORNIA, ASSIGNOR TO LOUIS S. LOEB, OF BERKELEY, CALIFORNIA

MIXING VAT

Application filed April 9, 1928. Serial No. 268,424.

The invention relates to a mixing vat particularly designed for the mechanical mixing of dry and powdery materials and having extending therethrough a shaft carrying mixing paddles.

A general object of the invention is to provide in a vat of the class described improved and particularly effective sealing means for the different openings thereof whereby the escape of dust therefrom during mixing may be prevented.

A more specific object of the invention is to provide a hinged lid for the vat in which the hinge means itself provides a dust tight joint.

Another object of the invention is to provide a dust-tight seat for the lid around the edge of the lid opening such that the weight of the lid is sufficient for providing the necessary sealing contact of the lid with the seat.

A further object of the invention is to provide a combined packing and bearing device for the paddle shaft, which device is particularly effective in protecting its bearings from dust from the vat.

A still further object of the invention is to provide a simple and efficient dust-proof outlet gate for the vat.

Yet another object of the invention is to provide improved mixing paddles and a mounting means therefor.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings,

Figure 1 is a plan view of the vat, portions of the structure being broken away.

Figure 2 is an enlarged view taken on the line 2-2 in Figure 1.

Figure 3 is a sectional view of the structure taken on the line 3-3 in Figure 1.

Figure 4 is a fragmentary and enlarged longitudinal sectional view through the vat.

Figure 5 is an enlarged sectional view of a paddle, taken on the line 5-5 in Figure 3.

Figure 6 is an enlarged fragmentary view taken on the line 6-6 in Figure 1.

Figure 7 is an enlarged and partly sectional view of a shaft bearing structure of the device.

Figure 8 is a side view, partly in section, of the showing of Figure 7.

Figures 9 and 10 are views taken generally on the lines 9-9 and 10-10 in Figure 7 of major elements of the structure.

As herewith particularly illustrated, the features of my invention are incorporated in the structure of a vat 11 preferably, though not necessarily, formed of sheet metal and having a shaft 12 carrying mixing paddles 13 extending therethrough and therefrom. In the present embodiment, the vat is in the form of a trough having plane ends 14 and a cylindrically curved bottom 16, with the axis of the shaft 12 lying in the axis of curvature of the bottom 16 whereby a complete stirring of material in the bottom of the vat may be insured. As shown, the sides 17 of the vat are plane and extend integrally upwardly from the side edges of the bottom 16 in flaring relation to terminate substantially in the plane of the top edges 18 of the ends 14. Support for the vat is provided by means of a suitable frame 19 to end members 21 of which the vat ends 14 are secured by bolts 22 or by riveting.

A discharge opening 22 is provided in the bottom of the vat, said opening being preferably disposed centrally of the bottom for a reason which will hereinafter appear. Closure means are provided at the opening 22, and as here shown, such means comprises a body member 23 fixed to and below the vat bottom at said opening and providing a passage 24 therethrough for registration with the opening 22. A gate member in the form of a plate 26 is slidably mounted in the body for movement transversely of the passage 24 whereby it may be disposed to close

the same or to leave it open. Preferably, and as shown, the plate 26 is rectangular and closely fits the opening 27 in which it is reciprocable.

5 The opening 27, it is noted, extends completely through the body, and a combined stop and sealing means is provided therein for engagement by the inner end of the plate 26 when the latter is disposed for closing the passage 24. Accordingly, and as shown, an opening 28 is provided through the body 23, said opening extending across the opening 27 in the plane thereof and being somewhat wider than the opening 27 10 transversely thereof. Preferably, and as shown, the opening 28 is of rectangular cross section to receive a strip of suitable packing 29 of like cross section, said packing being of a nature to seal the joint made therewith by the opposed plate edge. To facilitate the production and assembly of the outlet gate now described, the body 23 is here shown formed of upper and lower sections 31 and 32 respectively, said sections being 15 transversely separable in a horizontal plane extending generally centrally through the plate receiving opening 27. Bolts 33 are utilized to hold the body sections 31 and 32 together, and said bolts are extended 20 through the vat bottom with the heads thereof engaged against the inner side of said bottom whereby they serve also to secure the gate body to the vat. It will now be noted that the gate described is particularly efficient 25 in preventing the escape of dust therethrough when it is closed, operates in a particularly simple manner, and permits an unrestricted flow of the mixed materials through the passage 24 when the latter is 30 open.

Material to be mixed is arranged to be placed in the vat from the top thereof, and a cover 36 having at least a part thereof displaceable is accordingly provided for the vat. 35 Obviously, the cover 36 must afford a tight closure for the vat during a mixing of powdery elements to be mixed, as dust from many substances which might be mixed in the present vat would be dangerous or injurious. 40 As shown, the cover 36 is formed with fixed and movable sections 37 and 38 respectively, the section 37 being secured at the top of the vat to extend from a longitudinal edge 39 thereof over parts of the top edges 18 of the ends 14 to all of which edges it is secured. The movable cover section, or lid, 38 is hinged along the free edge of the cover section 37 by means which provide a dust-tight joint between and along the sections, and as shown, 45 such means comprises a strip 41 of flexible and dust-tight material joining the cover sections along the full length of their abutting edges. In this manner, a sealed hinge is provided in an extremely simple manner, it 50 being noted that both leather and rubberized

fabric have been found to be particularly satisfactory as materials of which the strip 41 may be made.

Special sealing means are also provided around those top edge portions arranged to be engaged by the lid 38, it being obvious that the metal-to-metal contact of no great width which would obtain if the lid 38 engaged the metal edges of the vat would provide a very inefficient seal. Accordingly, and as shown, 55 those edge portions of the vat which are arranged to underlie the lid 38 are formed to define a plane slightly below the plane of the vat edge portions which underlie the cover section 37, and a strip 42 of a resilient sealing material is secured along said lowered edge portion with its top edge lying substantially in said last plane. The material of the strip 42 is preferably of a somewhat resiliently yielding nature whereby a dust 60 proof seal may be provided between it and the cover section 38 when the latter is supported thereon. In this manner, the necessary seal is provided and the provision of special fastening means for the cover section 38 is rendered unnecessary.

Preferably, the sealing strip 42 is adjustably mounted in its position on the vat walls. Accordingly, this strip is here shown disposed between the walls and clamp plates 43 disposed on the outer sides of the walls with their top edges generally flush with the tops of the opposed wall portions. Bolts 44 are utilized to secure the plates 43 in position, such bolts extending through the vat 100 walls with their heads inside and through perforations 46 in the plates. The strip 42 is disposed above the bolts 44 and the plate perforations 46 freely receive the bolts whereby a screwing up of the nuts 47 of the bolts 105 is arranged to clamp the strip 42 in desired adjusted relation to the hinged lid 38. In this manner, the strip 42 may be adjusted to insure a properly sealed relation of the lid 38 to the vat when the lid is operatively disposed. Means are provided for supporting the lid 38 when open whereby an undue flexing of the hinge strip 41 may be avoided, and as shown such means comprises a plate member 48 secured to the back vat wall 17 and 110 extending upwardly of the fixed cover portion 37 to provide a rest at its top edge for supporting the lid 38.

Preferably, and as shown, the shaft 12 extends through openings 49 of both end walls 120 14 of the vats and is journaled in suitable bearings 51 mounted on the walls whereby it is entirely supported by the vat. Since, as hereinbefore mentioned, it is highly desirable that leakage of dust from the vat be prevented, and since most dusts are abrasive and so must be kept out of the shaft bearings, stuffing boxes 52 are provided for the shaft where it emerges from the vat and inwardly of 125 the bearings. The stuffing boxes and bear- 130

ings should preferably function independently and both must be supported from the vat ends in axially aligned relation. Accordingly, and as shown, these members are provided in a single structure 53 for mounting on the vat end walls, said structure providing for the operative independence of the bearing and stuffing box portions thereof.

The present, and preferred, combined packing box and bearing structure 53, it will now be noted, comprises a base member 54 arranged to be fixed against an end wall 14 at the perforation 49 thereof and is provided with a perforation 56 arranged to be disposed in registration with the wall perforation 49. The perforation 56 is arranged to closely receive the shaft 12 therethrough, but does not provide a bearing for the shaft. Extending from the base 54 in axial alignment with the perforation 56 thereof is a sleeve 57, the bore of said sleeve being of somewhat greater diameter than that of the shaft 12 whereby an annular stuffing box cavity 58 is defined about the shaft for the reception of suitable stuffing 59. An annular gland 61 is provided for mounting on the shaft and for slidably fitted engagement in the bore of the sleeve 57 whereby the packing may be compressed between it and the base portion at the perforation 56 thereof in a well understood manner. Ears 62 extend radially and oppositely from the gland 61, and are provided with axial perforations 63 for the reception of bolts 64 by which the gland 61 is arranged to be forced and held against the packing with the necessary pressure. As shown, the bolts 64 lie outwardly of the sleeve 57 and extend through perforations provided in the base 53 and the underlying wall portion. Preferably, the ears 62 are horizontally disposed, so that if dust of the material being mixed in the vat should escape through the stuffing it would fall freely from the stuffing box and so be kept out of the bearings, this feature being an important one in the present device.

Extending axially from and along the sleeve 57 at the top and bottom thereof are posts 66, said posts being in diametrically opposed relation and extending somewhat beyond the free end of the gland. The posts 66, it is noted, provide a mounting for the bearing 51 and preferably comprise integral parts of the structure of the base 54. The bearing structure, it will now be noted, comprises a cylindrical casing 67 having provided at one end thereof a radially extending flange 68 for engagement against the ends of the posts 66, the bearing surfaces of said flange and posts being machined for seated, and preferably stepped, engagement with each other. Preferably, and as shown, central portions of the opposed surfaces of the flange 68 and posts 66 are depressed whereby only radially inner and outer portions of said surfaces provide the bearing between these

members. Bolts 69 are provided for securing the casing flange 68 to the posts 66, and as here shown such bolts extend longitudinally through the posts for engagement through the base 54 and wall 14 whereby they also serve to provide the primary means for securing the structure to the wall. Preferably, and as shown, the post portions intermediate the ends thereof and in the line of the bolts 69 are cut away from the outer sides of the posts whereby the structure is considerably lightened.

A centrally perforated wall 71 provides a closure for the outer end of the cavity of the casing 67, and a bushing 72 is mounted in the bore of said sleeve adjacent the end wall 71 thereof. Preferably, and as shown, the bore of the bushing 72 defines an annular space about the shaft 12 in which a set of roller bearings 73 is disposed. A circumferential groove 74 is provided in the bore of the casing 67 opposite the bushing 72, said groove being connected with an oil cup 76 mounted on the casing, and the bushing is provided with a perforation 77 opposite the groove 74 whereby oil from the cup is arranged to be delivered to the bearings 73.

Means for preventing a leakage of oil inwardly along the shaft toward the vat is preferably provided as part of the bearing structure, and as here shown such means comprises a cup shaped member 78 having its bottom axially perforated to receive the shaft 12 therethrough and disposed in the bore of the casing 67 with its bottom toward the bearings 73. The inner end of the member 78 is closed by means of an annular disc 79 encircling the shaft, and stuffing 81 is disposed in the cavity thus defined, whereby an oil tight seal may be provided about the shaft. The free edge 82 of the member 78 is formed to provide an outwardly extending flange, and this flange is arranged, when the bearing structure is assembled, to be engaged between the inner end of the casing 67 and projections 83 extending radially inwardly from the posts 66 whereby a definite positioning of the member 78 is effected. It will be noted that enough clearance is provided between the bearing structure now described and the end of the stuffing box sleeve 57 to permit a complete axial removal of the gland 61 from within said sleeve to permit a renewal of the stuffing 59 therein without necessitating the removal of the bearing structure. And it will be further noted that the present means of combining the bearing 51 and stuffing box 52 as part of a single unitary structure insures proper centered relation of these elements and produces a particularly compact and efficient unit for the purpose for which it has been designed.

The paddles 13, it will now be noted, are mounted on hubs 84, here shown formed with cooperating sections 86 and 87 arranged to

be bolted together about the shaft 12 whereby the hubs may be independently mounted on the shaft, the sections 86 carrying the paddle blades 88 extending radially therefrom as integral portions thereof. The blades 88 are preferably formed with plane forward faces 89, and such faces are preferably angularly related to the shaft axis whereby, as the shaft is rotated, material being mixed will be urged axially along the shaft in a direction determined by the disposal of the blade faces 89. In the present embodiment, eight paddles 13 are arranged to be mounted on the shaft 12 within the vat 15 cavity, with the four blades nearest to each end set to urge material from such end toward the middle of the vat, beneath which the discharge opening 22 is provided. In this manner, a stirring of the material while 20 the discharge gate is open will deliver the material at such gate, and the material is urged away from the exit points of the shaft through the vat ends 14 during use of the vat.

25 Openings 91 are preferably provided in the paddle blades 88 adjacent their ends, such openings having been found to appreciably increase the rate and thoroughness of mixing effected by the device. Preferably, and 30 as shown, the openings 91 are smallest at their inlet ends and are generally blade shaped in outline with their narrow ends toward the shaft.

It will now be noted that the present device is particularly designed for mixing dry powdered materials having ingredients the dust of which is injurious to organic or inorganic matter, particular reference being made to ingredients of paints, calcimines, 40 insecticides, etc. The present structure, through its various sealing features, prevents the escape of dust during mixing and so prevents waste and possible injury to an operator or the structure in which the apparatus 45 is housed. It is not intended, however, to so limit the use of the apparatus as the mixing of liquids with other liquids or with dry materials may be effected by use of the present apparatus without change in the essential structure thereof.

50 I claim:

1. In a vat for mixing dry materials and having a discharge opening at the bottom thereof, a member providing a discharge 55 passage in registration with said opening and a guideway extending therethrough transversely of said passage, a gate member frictionally and slidably engageable in said guideway for closing said passage, and a 60 resilient sealing member in said guideway arranged to be engaged by an end of said gate member when the member is in passage closing position.

65 2. In a mixing vat having a discharge opening at the bottom thereof, a member pro-

viding a discharge passage in registration with said opening and a guideway extending therethrough transversely of said passage, said member being formed in sections separable at the plane of said guideway, a gate member frictionally and slidably engageable in said guideway and disposable therein to close said passage, a resilient sealing strip in said guideway arranged to be engaged by an end of said gate member when in passage closing position, and cooperating means on the sections of said member for releasably securing said strip in operative position in the guideway.

In testimony whereof, I have hereunto set 80 my hand at Oakland, California, this 3rd day of April, 1928.

JOHN R. KUENEMANN.
